MOTOR-DRIVEN HAMMER

Karl Axel Ragnar Erfass, Stockholm, Sweden

Application March 9, 1935, Serial No. 10,274
In Sweden July 23, 1934

7 Claims. (Cl. 125—33)

My invention relates to an improvement in hammers of the kind provided with a striking member, which receives a reciprocating motion from a motor in order to act upon a tool. In such hammers the connection of the striking member with the motor shaft for transforming the rotation into a reciprocating motion generally consists of a cross-head and a joint link extending from the said cross head to the piston-like striking member. Said member consists of two parts arranged one after the other in relation to the stroke, the outer part constituting the striking body proper. The said two parts are resiliently connected with each other.

An object of my invention is to arrange an air space in the connection between the said two parts in such a manner that an air cushion is formed which in cooperation with the resilient connection considerably improves the action of the hammer, as will be seen from the following.

Another object is to provide the said air space with one or more air inlets, which are opened, when the upper part of the striking member moves upward by means of its connection with the cross-head, but are closed when the said part moves downward, the air being compressed in the air space and transmitting the movement of the outer part of the striking member.

A further object is to provide the hammers with means to lubricate some faces of the two parts of the striking member, the said faces being movable relatively to one another and sliding one within the other, the inner part is provided with oil holes leading to the said faces, which slide one within the other.

The invention is illustrated by way of an embodiment in the accompanying drawing, in which a hammer improved according to this invention is shown in side view and partial section.

Figure 1 shows a partial cross section of the embodiment in its entirety,

Figure 2 shows a side view of a detail and

Figure 3 is a side view of a modification of the same detail.

Figure 4 is another side view of said modification.

By means of a pinion 1a and a toothed ring 1b the motor 1 drives a cross-head 2, which by means of a ball bearing 17 is rotatably mounted in a holder 3 and by means of a link 4 provided with ball joints 18, 19 is connected with the upper or inner part 6 of the striking member. The lower or outer part 7 of said member i. e. the striking body proper is provided with cylindrical end portions 8, 9. The upper portion 8 constitutes

a sleeve in which the portion 6 of the striking member is movable. Between the two parts 6, 7 I provide a spring 5 in such a manner that the striking body 7 hangs by the spring, when the hammer is held in a vertical or inclined position. 5 The lower cylindrical sleeve shaped portion 9 surrounds a guide 10 for the tool and between the said portion 9 and the lower portion 15 of the hammer casing I provide a buffer spring 11, which prevents the part 7 from striking against 10 the part 10 in case the tool is removed from the same.

According to my invention I arrange between the two parts 6, 7 of the striking member an air space 16 in the cylindrical portion 8, which space 15 may be filled with air by air inlets 12, so that the upper part 6, which forms a piston 6a moving in the said space will not act direct upon the striking body 7 but only by means of the air cushion formed in the said air space. Losses of air, 20 if any, in the space 16 are compensated for by air entering through the air inlets 12, when the upper part 6 of the striking member has uncovered the same for example by action of the spring 5.

In the piston 6a there is an oil chamber 13, which by means of holes 14 communicates with the faces of the two parts of the striking member, which slide one within the other, so that the said faces may be effectively lubricated.

By the provision of the said air cushion the spring 5, due to the servo action of the air cushion, may be made comparatively weak, so that during the subsequent working stroke of the striking body it may be easily stretched thereby increasing the elasticity thereof and making the length of the stroke greater than that of the connecting rod. In addition hereto a vibrationless recoil and a stronger blow is obtained as an essential feature of my hammer.

To completely utilize the favorable action of the air cushion it is necessary to fix the spring steadily to the part 6 and to the striking body 7. In view hereof I have provided each of them with a portion for fixing the spring, which is effective as well as simple. To explain this detail the said portion of the striking body for fixing the spring is viewed from the side in Figure 2. The exterior of the striking body is provided with two flanges 20, 21, which form a peripheric 50 groove 25 for the appertaining end winding of the spring. Due to its own resilience the largest part of the said end winding is steadily disposed in the groove but the winding continues through an opening 22 in the flange 20. Hence, the part 55

of the spring, disposed in the groove, is located in a plane perpendicular to the axis of the striking body. After a bend 24 the spring extends spirally as usual. The spring contacts the striking body only near and in the groove, by which the striking body may move freely within the spring in its longitudinal direction but yet be steadily fixed to the spring. The fixing portion of the part 6, i. e. at the opposite end of the spring, is made in the same way. The spring winding is introduced into its groove thereby that the spring, after having been put on the part 6 (or 7), is turned relatively to the said part in such a manner that one end 23 of the flange 20 enters between the spring end and the next winding. It is then turned further until the spring end has passed almost around the part, i. e. until the bend 24 meets the flange end 23.

20 The spring may also be fixed in such a manner that in the portion surrounded by the spring windings at one or both ends of the spring there is a groove 26 (Figure 3) for one or more of the windings of the spring, the said groove, when seen from the entering end, extending some way *a* spirally with the pitch of the spring and after that some way *b* in a plane perpendicular to the axis of the spiral. When the end winding of the spring is turned in the last mentioned part *b* of the groove to a stop *c* (Figure 4), it will be steadily fixed in the groove because the groove direction deviates from the regular spiral of the spring.

Naturally, I may use my invention also in other hammers than the one shown in the drawing.

Having now described my invention, what I claim as new and desire to secure by Letters Patent is:

1. In motor-driven hammers means for transforming a rotation motion into a reciprocating one and for transmitting said reciprocating motion to a striking member, two parts arranged one after the other in relation to the stroke and constituting said striking member, elastic means connecting said two parts to each other for obtaining a movement of the parts in relation to each other, and the provision of a buffer air cushion in the connection between the two parts, which constitute the striking member.

2. In motor-driven hammers means for transforming a rotation motion into a reciprocating one and for transmitting said reciprocating motion to a striking member, two parts arranged one after the other in relation to the stroke and constituting said striking member, elastic means connecting said two parts to each other, one of the parts forming a pump-cylinder and the other the appertaining piston, which is adapted to move along the path of the striking strokes, said cylinder containing air, which constitutes a buffer air cushion acting when the pump chamber is decreasing.

3. In motor-driven hammers means for transforming a rotation motion into a reciprocating one and for transmitting said reciprocating motion to a striking member, two parts arranged one after the other in relation to the stroke and

constituting said striking member, elastic means connecting said two parts to each other, one of the parts forming a pump cylinder and the other the appertaining piston, which is adapted to move along the path of the striking strokes, said cylinder containing air, which constitutes a buffer air cushion acting when the pump chamber is decreasing, the provision of air inlets leading to the pump chamber containing the air cushion so as to make it possible to supply fresh air to be substituted for air which may have escaped. 5

4. In motor-driven hammers means for transforming a rotation motion into a reciprocating one and for transmitting said reciprocating motion to a striking member, two parts arranged one after the other in relation to the stroke and constituting said striking member, elastic means connecting said two parts to each other, one of the parts forming a pump cylinder and the other the appertaining piston, which is adapted to move 20 along the path of the striking strokes, said cylinder containing air, which constitutes a buffer air cushion acting when the pump chamber is decreasing, the provision of oil intakes in those faces of the parts of the striking member, which 25 slide one within the other, said intakes communicating with an oil chamber within the pump piston.

5. In motor-driven hammers as claimed in claim 1, in which the two parts of the striking member are united by means of a screw spring, by which the striking body proper hangs the spring being connected to a cylindrical portion of one of the parts at least, said portion being provided with a groove for at least the outermost 30 spring winding, in which the said winding is clamped by its own resilience in a plane perpendicular to the axis of the cylinder or the spiral.

6. In motor-driven hammers as claimed in claim 1, in which the two parts of the striking 40 member are united by means of a screw spring, by which the striking body proper hangs the spring being connected to a cylindrical portion of one of the parts at least, said portion being provided with a groove for at least the outermost 45 spring winding, in which the said winding is clamped by its own resilience in a plane perpendicular to the axis of the cylinder or the spiral, the groove being peripheral and merging into a side opening through which the spring winding continues in its normal spiral where it has no contact with the cylindrical portion.

7. In motor-driven hammers means for transforming a rotation motion into a reciprocating one and for transmitting said reciprocating motion to a striking member, two parts arranged one after the other in relation to the stroke and constituting said striking member, a spring connecting the two parts to each other for obtaining a movement of the parts in relation to each other, 60 at least one of the parts having a cylindrical portion provided with a groove for at least the outermost winding of the spring, said groove running partly helically, partly peripherically so that the said winding is clamped by its own resilience in the groove. 65
